US0D1017763S

(12) **United States Design Patent** (10) **Patent No.:** **US D1,017,763 S**
Zhang et al. (45) **Date of Patent:** **** Mar. 12, 2024**

(54) **FUEL TANK**

(71) Applicant: **CHONGQING LIDONG MACHINERY & ELECTRIC CO., LTD**, Chongqing (CN)

(72) Inventors: **Qiping Zhang**, Taizhou (CN); **Zhongbing Zhu**, Taizhou (CN); **Daoyong Chen**, Taizhou (CN); **Guolin Lu**, Taizhou (CN)

(73) Assignee: **CHONGQING LIDONG MACHINERY & ELECTRIC CO., LTD**, Chongqing (CN)

(**) Term: **15 Years**

(21) Appl. No.: **29/857,390**

(22) Filed: **Oct. 21, 2022**

(30) **Foreign Application Priority Data**

Sep. 30, 2022 (CN) 202230655847.9

(57) **CLAIM**

The ornamental design for a fuel tank, as shown and described.

DESCRIPTION

FIG. 1 is a top perspective view of a fuel tank showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
